UNITED STATES PATENT OFFICE.

PARIS R. FORMAN, OF CHICAGO, ILLINOIS, ASSIGNOR TO NATIONAL PNEUMATIC COMPANY, OF NEW YORK, N. Y., A CORPORATION OF WEST VIRGINIA.

DOOR-OPERATING MECHANISM.

Application filed August 23, 1917. Serial No. 187,903.

To all whom it may concern:

Be it known that I, PARIS R. FORMAN, a citizen of the United States, residing at Chicago, in the county of Cook, State of Illinois, have made a certain new and useful Invention in Door-Operating Mechanism, of which the following is a specification.

This invention relates to door operating mechanism, and particularly to mechanism of the fluid pressure operated type.

The object of the invention is to provide a door operating mechanism of simple structure which is efficient in operation and economical of manufacture, which may be readily applied without additional equipment to the present manually operated doors, such as are used on street cars, trains, subway or elevated.

Further objects of the invention will appear more fully hereinafter.

The invention consists substantially in the construction, combination, location and relative arrangement of parts all as will be more fully hereinafter set forth, as shown by the accompanying drawings and finally pointed out in the appended claim.

Referring to the drawing;

Fig. 1 is a view in elevation and partly in section of the platform and a portion of the body portion of a car.

Fig. 2 is a top plan view of the door operating mechanism shown in Fig. 1.

Fig. 3 is a sectional view in elevation thereof.

Fig. 4 is a sectional view taken on the line 4—4, Fig. 3 and looking in the direction of the arrows.

Fig. 5 is a top plan view of Fig. 1 with the roof of the car removed.

Fig. 6 is a horizontal sectional view of a modified form of motor employed in accordance with my invention.

Fig. 7 is a view in front elevation of the same.

Fig. 8 is a vertical sectional view of a still further modified construction of motor employed in accordance with my invention.

Fig. 9 is a sectional view taken on the line 9—9 Fig. 8 and looking in the direction of the arrows.

Fig. 10 is a similar view taken on the line 10—10, Fig. 8 and looking in the direction of the arrows.

Fig. 11 shows another form of arrange-

ment of parts which will accomplish the purposes of my invention.

Fig. 12 is a similar view of a modified structure of motor employed in accordance with my invention.

Fig. 13 is a top plan view of the same slightly enlarged.

Fig. 14 is a vertical sectional view of the same.

Figs. 15 and 16 are diagrammatic views showing the pneumatic control of the motors.

The same part is designated by the same reference numeral wherever it occurs throughout the several views.

It is among the special purposes of my present invention to provide a simple and efficient type of construction of motor which alone can be added to the present manually operated door operating mechanism to

thereby convert the same from the manual control to the pneumatic control. The advantage of this arrangement is apparent in that where the doors at present are opened and closed by manual exertion, in the arrangement of my invention the only manual exertion required is to shift a valve which

controls the pneumatic motor and which in turn opens and closes the doors. At the present time, where it is contemplated to employ women conductors for various reasons, and where the actual manual labor in controlling the doors must be minimized, my present invention is especially adapted.

In a great many types of structures now in use, the conductor's station is in the form of a barrier which divides the body of the car into separate passageways to thereby effectively form a fare prepayment station and divide the incoming from the outgoing passengers.

In this type of car, it is customary to mount the door control mechanism at the conductor's control station and my present invention is especially adapted to cars of this type. While the particular

type of door operating connections for actually operating the door from the control station forms no part of my present invention, I have shown what has now become standard in the art, as one form that may

be readily employed in connection therewith, namely, the type of operating connections shown in U. S. Patent to Rowntree 1,067,787, patented July 15th, 1913, which

consists substantially in the connections

and 2 connected to the respective shafts 3 and 4 of the door which connections are secured to a shaft 6 enclosed within a hollow standard 5 whereby when said shaft 6 is rotated, the shafts 3 and 4 of the doors are rocked to thereby open or close the doors indicated generally at 7, in the usual well known manner. If desired, and as shown, both in the above identified patent and the present case, the operation of the shaft 6 may simultaneously control the operation of a foldable step 8, as shown, the conductor's station is at the standard 5, which is located in the center of the car platform at the portion thereof which leads into the car body to divide the car body into separate passageways as above explained. In some types of cars there is a riser 9 or step leading from the car platform to the car body floor 10. See Fig. 1. It is customary in cars of this description to locate the standard 5 at the edge of the riser 9 and to hold the same in position by means of suitable brackets 11. The shaft 6, located within the standard 5, heretofore has been operated manually by means of a hand lever secured to the shaft and located at the top of the standard 5 as clearly shown in the Rowntree patent above identified. It is among the purposes of my present invention to substitute for the manually operated handle a pneumatic motor mechanism controlled by a valve and which in turn is controlled by a manually operated handle. Any type of motor may be employed in this connection and I have shown and will now describe various types with details of construction which are economical of manufacture and efficient for the purpose required.

Referring to Figs. 1 to 5 inclusive, I show one type of motor 20 which may be readily employed in accordance with my invention. The motor 20 comprises a comparatively large cylinder 21 vertically disposed and thus parallel to the standard 5 and shaft 6. A piston 22 operates in the cylinder 21 and is connected by means of a piston rod 23 to piston 24 of relatively smaller size than piston 22 which operates in a relatively small cylinder 25. The shaft 6 extends upwardly through the standard 5 into the casting 20 as shown and is provided at its top end with a tortuous groove 26 thereabout. A bracket 27 is secured to the piston rod 23 in any suitable manner and surrounds the top of the rod 6 and is provided with a projection 29 which engages in the tortuous groove 26 of the top of the shaft 6. When the doors are in their closed position the parts are as shown in Fig. 3. To open the door fluid pressure is admitted behind the piston 22, causing the pistons 22 and 24, and their connecting rod 23 to move downwardly. This, it will be seen, causes the bracket 27, which is secured to the connect-

ing rod 23, to move downwardly therewith, and to the projection 29 of the bracket 27, working in the groove 26 at the top shaft 6, causes the shaft 6 to rotate, thus actuating the door to open the same. The manually operated valve for controlling the fluid pressure to and from the motor 20 is shown at 30 and is located adjacent the motor 20 as indicated.

In the patent to Rowntree above identified, the conductor's stand is shown at its top to be formed in the shape of a hand rail or grab rail. If desired, this feature may be retained in the mechanism of my invention. And for that purpose, I have shown the hand grab 31 in Fig. 2, as being secured to or forming a part of the casting of the motor 20. Another type of vertically operating motor I show in Figs. 8, 9 and 10. In this construction, I employ the differential cylinders 35, 36, with the modification that the cylinder 36 forms a continuation of the standard 5 which incloses the shaft 6. The top of the shaft 6 is provided with the tortuous groove 26, as in the type of motor discussed, hereinbefore. The portion of the shaft 6 in this instance however, which is provided with a tortuous groove, extends through suitable packing, through the smaller piston 24 and into the connecting rod 23, which connects the smaller piston 24 and the larger piston 22. The end of the interior bore of the piston connecting rod 23 is provided with the projection 29 which engages in the groove 26 of the end of the shaft 6. Likewise, the connecting rod 23 is provided with a projection 37 which slides in the guide 38 which forms a part of the casting of the motor to prevent the pistons from revolving in their respective cylinders. Thus it will be seen that if fluid pressure is admitted behind the smaller piston 24, if the parts are in the position shown, the pistons 24 and 22 will move upwardly, being prevented from rotation, as above explained and the projection 29 of the piston 24 moving upwardly in the tortuous groove 26 of the top of the shaft 6, will rotate the shaft. In Figs. 12, 13 and 14, I show another type of vertically operating motor, which consists substantially of the casting 40 provided with the cylinder 41 of relatively large bore and the cylinder 42 of relatively small bore in which operates respectively pistons 43 and 44 of sizes corresponding to the respective cylinders. The shaft 6 located within the standard 5 is located between these two cylinders and is provided at its top end with a bevel gear 45 which meshes with the segment gear 46 pivotally carried at 47 by the casting 40. One end of the segment 46 is secured by the link 47^a to the piston 43, the connection between the link and the piston and the segment gear being pivotal as shown. A similar link 48

secures the other end of the segment gear 46 to the piston 44 as shown. The parts are shown, as will be hereinafter described, in the position which indicates that the doors 6 of the car are closed. To open the door fluid pressure is admitted behind the piston to larger diameter, namely 43, thereby rocking the segment gear 46 about its pivotal connection 47^a, thus causing the piston 44 to 10 travel downwardly in its cylinder 42 and simultaneously rotating the bevel gear 45 of the shaft 6, thus securing the operating movement of the shaft 5, to open the door. It is apparent that the reverse operation will 15 rotate the shaft 6 in the opposite direction and thus secure the closing movement of the door. I have shown this type of motor in Figs. 12 and 13 as provided with the hand grab 31. It is obvious however, that I am 20 not to be limited to this detail. In Figs. 6 and 7, I show what I will term a horizontal type of motor which may be employed in accordance with my invention. I have shown this construction being of the differential cylinder type comprising a cylinder 50 of large diameter and a cylinder 51 of small diameter in which parts respectively are located the pistons 52 and 53, which pistons are connected together by means of the 25 rack bar 54, which rack bar meshes with and rotates a gear wheel 55 carried by the shaft 6. The control handle 30 operates the valve which controls the admission and exhaust of the fluid pressure to and from the motor. 30 I have likewise shown this type of motor provided with a hand grab or rail 31. It is apparent that all moving parts are completely enclosed within the standard so that in effect the motor itself becomes a portion 35 of the hand rail or grab. As shown in Fig. 11, a motor of this type of construction may be located on the riser 9 leading to the car floor 10 and clamped thereto by suitable clamps 60. This particular location of the 40 motor, however, forms no part of my present invention.

In Figs. 15, 16 and 17, I show the fluid pressure connections for controlling the supply of fluid pressure to and from the 45 motor, and while I have shown it as applied to the type of motor shown in Figs. 6 and 7, it is apparent that the same system of control may be employed for all of the motors herein described. The piston 52 of 50 larger diameter, and the piston 53 of smaller diameter, is in each case employed. The valve indicated at 70 which controls the motor is provided with a connection 71 to the source of fluid pressure and a connection 72 to open air or exhaust. The 55 valve is connected by line 73 to the end of the cylinder of large diameter and the end of the cylinder of small diameter behind the piston 53 continuously in connection with the source of fluid pressure 60 through the pipe line 71. The valve is in communication with the source of pressure through port 74. The pipe line 73 communicates with the valve through port 75. The exhaust 72 communicates with the valve through port 76. An additional port 77 communicates by means of pipe line 78 to the cylinder of larger diameter at a point mid-length therein. These parts are 65 fixed in the valve seat adjacent the rotatable portion of the valve. The rotatable portion of the valve 70 is provided with passages 80 and 81 therein so that when properly positioned the passage 80 establishes communication between the port 74 and port 75, as shown in Fig. 15, and likewise will establish communication between the port 77 and through restricted opening 83 with port 75 in its other extreme position as 70 shown in Fig. 16. From this, it is seen, that fluid pressure is at all times admitted behind the piston 53 of smaller diameter so that when the doors are all closed and the 75 ports are in a normal position as shown in Fig. 15, the pistons are in their extreme left position, as shown in said figure. To open the door, the valve is moved on its seat to the position shown in Fig. 15, whereby fluid pressure is admitted from 80 source 71 to port 74, to passage 80 of the rotary valve, to port 75, line 73 to the motor, and behind the piston 52. Thus the pressure behind each of the pistons is equalized but piston 52, being of larger diameter than the piston 53, the pistons move to the right 85 against the pressure which at all times is maintained against the smaller piston 53, and the doors are thus in their open position and the motor is in the position shown in Fig. 16. To close the doors, it is merely 90 necessary to exhaust the cylinder of piston 52 and to effect this condition the valve assumes the position shown in Fig. 16, whereby the port 74 is severed from communication with the port 75, as shown, and 95 the port 77 is placed in communication with the port 76 and consequently with the exhaust 72. Thus there is a free flow of fluid pressure behind the piston 52 through the line 78, ports 77 and 76, to exhaust 72, until 100 the travel of the piston 52 to the left covers the opening of the pipe line 78 into the cylinder of the piston 52. There is, however, communication from the cylinder of piston 52 through pipe line 73, port 75, restricted 105 openings 83 to the exhaust 72, which allows the pistons 52 and 53 to move to their extreme left position and at the same time securing a proper cushioning action for the 110 last closing movements of the top to thereby prevent slamming. Many other details and arrangements embodying the principles of my invention will occur to those skilled in the art without departing from the scope of 115 my invention, as defined in the claim.

Therefore, I wish it to be understood that my invention is not to be limited to the details of construction set forth hereinbefore.

Having now set forth the objects and nature of my invention and having shown and described various embodiments thereof, what I claim as new and useful and of my own invention and desire to secure by Letters Patent is:—

10. In a car, the combination with a platform, a doorway, for said platform, a door for said doorway, connections between said door to a point on said platform at a distance from said doorway, a shaft for controlling

said connections extending vertically from said platform a hollow standard for enclosing said shaft, a gear located at the end of said shaft and secured thereto to rotate therewith, a rack bar meshing with said gear, said rack forming a connecting rod between the pistons of a fluid pressure actuated motor said motor being supported by said standard, and means for controlling said motor.

In testimony whereof I have hereunto set my hand on this 16th day of August, A. D. 1917.

PARIS R. FORMAN.
